SHOE

Jack Abowitz, New York, N. Y.

Application July 21, 1950, Serial No. 11,285

Term of patent 3½ years

(Cl. D7—7)

To all whom it may concern:

Be it known that I, Jack Abowitz, a citizen of the United States of America, residing in New York, county of New York, and State of New York, have invented a new, original, and ornamental Design for a Shoe, of which the following is a specification, reference being had to the accompanying drawing, forming part thereof.

Fig. 1 is a front perspective view of a shoe, showing my new design.

Fig. 2 is a perspective view of the opposite side shown in Fig. 1.

I claim:

The ornamental design for a shoe, substantially as shown.

JACK ABOWITZ.
